SPINNING ROPE

James R. O'Neil, San Francisco, Calif.

Application November 7, 1932. Serial No. 641,635

8 Claims. (Cl. 46—37)

My invention relates to improvements in spinning ropes, and it consists of the combinations, constructions and arrangements hereinafter described and claimed.

5 An object of my invention is to provide an improvement over the form of the invention shown in my co-pending application, Serial No. 641,634, filed November 7, 1932, in which I set forth a miniature spinning rope having a fixed loop and 10 stem, with weights equally distributed around the loop, these weights being in the form of knots or sleeves.

In the present invention, I show a larger spinning rope with an adjustable stem. In this form 15 of the device, the loop is fixed as to length and is provided with a number of weights, which may be disposed equal distances around the loop. The stem is rotatably connected to the loop, and in this way, I do away with the necessity of providing a collar or sleeve on the stem. The stem 20 is also provided with knobs at both ends, these knobs being of different weights for performing different types of rope-spinning tricks.

Other objects and advantages will appear in 25 the following specification, and the novel features of the device will be particularly pointed out in the appended claims.

My invention is illustrated in the accompanying drawing forming a part of this application, 30 in which

Figure 1 is a perspective view of the device showing it in spinning operation;

Figure 2 is an enlarged view showing how the adjustable stem is connected to the loop; and 35

Figure 3 shows a modified form of weight used on the loop.

In carrying out my invention, I provide a cord 1 which is formed into a fixed loop 2 and provided with a number of weights consisting of figure 40 8 knots, numbered 3. These knots are preferably disposed equal distances from each other and form the connecting point of an adjustable stem 4 with the loop. Figure 1 clearly shows how the ends 5 and 6 of the loop 2 are secured to each other at 7 and 8 to form an opening 9 that slidably receives the stem 4. The stem 4 is formed from a piece of the cord forming the loop and is therefore flexible.

A wooden knob 10 is secured to one end of the 50 stem 4, and a second knob 11 is secured to the other end. The knobs are of different weights and this can be accomplished by making them of different materials having different specific densities, or the knobs may be made of the same 55 material and made of different sizes. In Figure

2, I show how the knob 11, for example, bears against the loop 2 and how the stem 4 is not only adjustably received in the opening 9, but is also rotatably received therein. The knob 10 or 11 disposed adjacent to the loop is used as a weight and functions with the other weights in aiding in opening the loop during spinning.

The over-all length of the loop may be varied slightly by tightening or loosening the knots 3 in the same manner as set forth in my co-pending application. Sleeves 12, see Figure 3, may also be substituted for the knots 3, if desired, and these sleeves may be adjusted along the cord 1 to balance the rope in any desired manner. The connection of the stem with the loop functions in the same manner as a weighted swivel in that it aids in balancing the loop.

From the foregoing description of the various parts of the device, the operation thereof may be readily understood.

The spinning of this device is accomplished in the same manner as that set forth in my co-pending application. The loop is larger than in the co-pending case and is therefore provided with a greater number of weights so that a light cord 80 may be used and still function in the same manner as a heavier cord.

The various advantages set forth for the device shown in the co-pending application are also obtained in the present case, and the additional 85 advantage lies in the fact that a sleeve on the stem is dispensed with because the stem itself is rotatably connected to the loop. With certain types of tricks, the heavier weighted knob 11 bears against the loop 2, while in other types of tricks, 90 the stem 4 is pulled through the opening 9 so that the other knob 10 bears against the loop.

While I have shown only the preferred forms of my invention, it should be understood that various changes or modifications may be made within 95 the scope of the appended claims without departing from the spirit of the invention.

I claim:

1. A spinning rope comprising a loop of fixed length, an adjustable stem slidably connected therewith and different sized weights disposed at the ends of the stem.

2. A spinning rope comprising a loop of fixed length and having an eye formed therein, and a stem slidably and rotatably received in the eye.

3. A spinning rope comprising a loop of fixed length, an adjustable stem connected therewith, and weights carried by the loop.

4. A spinning rope comprising a loop of fixed length and having an eye formed therein, a stem

slidably and rotatably received in the eye, and knobs secured to the ends of the stem for limiting the movement of the stem in the eye.

5. A spinning rope comprising a loop having an eye formed therein, a stem received in the eye and having a knob disposed at the end designed to contact with the loop, and weights disposed on said loop, said knob also acting as a weight.

6. A spinning rope comprising a loop having an eye formed therein, a stem received in the eye and having a knob disposed at the end designed

to contact with the loop, and weights disposed on said loop, said knob also acting as a weight, said weights being disposed equal distances from each other.

7. In a spinning rope, a stem, a loop having an eye for slidably receiving the stem, said stem having knobs of different weights disposed at its ends.

8. A spinning rope comprising a loop of fixed length, and a stem having a swivel connection with the loop adjacent to the place of joining.
